UNITED STATES PATENT OFFICE.

WINFIELD S. DRISCOLL AND WALTER F. DAVIS, OF GRETNNA, NEBRASKA.

CURRENT-WHEEL.

1,305,888.

Specification of Letters Patent. Patented June 3, 1919.

Application filed September 30, 1918. Serial No. 256,179.

To all whom it may concern:

Be it known that we, WINFIELD S. DRISCOLL and WALTER F. DAVIS, citizens of the United States, residing at Gretna, in the county of Sarpy and State of Nebraska, have invented certain new and useful Improvements in Current-Wheels, of which the following is a specification.

The present invention is a power device to be operated by either water or air currents.

10 One of the objects of the invention is to produce a cheap and simply constructed wind or water wheel of the above type, which permits of manual angular adjustments of its vanes during operation and which is efficient in operation.

The invention further resides in sundry details of construction which will be herein-after more fully described and claimed.

20 With reference to the accompanying drawings, which illustrate the preferred embodiment of the invention as now devised;

Figure 1 is a top plan view of the current wheel with the vanes adjusted to inoperative

25 position,

Fig. 2 is a side view of the wheel with the vanes in extended position and having portions shown in section to more clearly illustrate details of construction, and

30 Fig. 3 is a fragmentary detail section of a modified construction of the vane adjusting mechanism.

With particular reference to the drawings, 1 denotes a wheel, to be arranged preferably in horizontal position, mounted fast on a shaft 2 supported in suitable bearings at its end portions. The wheel as here shown is clamped on the shaft 2 between plates 3 and 4, which may or may not be adjustable on 35 said shaft, as may be desired. The wheel has, preferably, depending from its under side a plurality of vanes 5 having one of their longitudinal edges positioned radially relatively to the shaft 2 and hinged to the 40 wheel 1 by any suitable means, such as indicated by 6. With this construction the vanes will drop under their own weight and normally lie at right angles to the wheel, thus presenting their side faces to the pressure of 45 the fluid current—water or wind as the case may be.

Mounted preferably on the upper face of the wheel 1, is a shiftable vane adjusting member 7, in the form of a ring having 55 spokes or radial arms 7^a connecting it to a hub 7^b surrounding the shaft 2. Each vane 5

is connected to the ring 7 by a chain 8, or other flexible member, which has one end thereof secured to the vane, preferably, at an outer corner of its distal edge, and its other 60 end connected to the ring at a point 9 to the rear of the vane. All the vanes are correspondingly connected to ring 7 in order that there will be similarity of action among them. Therefore, with this construction, assuming that the pressure of the current is in the direction indicated by the arrows X in Fig. 1, the pressure will be exerted on the vanes at the left side of the wheel which are maintained in their extended position by the 70 chains 8, it being obvious that the vanes at the right side of the wheel will be collapsible or folded by said pressure to the position indicated by dotted line in Fig. 1, but will successively drop to extended position and present their side faces to the current pressure as the wheel 1 is rotated. This same operation will occur regardless of the direction or quarter from which the fluid current comes.

Now under certain conditions, it is desirable to vary the extended positions of vanes, or in other words to vary the degree the vanes will open from their collapsed position. This is accomplished by rotatably shifting the ring 7 relatively to the wheel 1 80 in the direction necessary to make the adjustment desired. This movement of the ring will lengthen or shorten the distance between the pivoted edge of each vane and the points of connection 9, thereby permitting the vane to normally lie perpendicular to the wheel 1 or at an acute angle thereto. This adjustment, however, does not hinder the vane from collapsing under the current pressure to lie in juxtaposition relative with 85 the wheel 1. The rotatable adjustment of the ring 7 is, preferably, obtained by a hollow shaft 10, through which the shaft 2 extends, having a gear or segment 11 thereon meshing with internal teeth on the hub 7^b of 90 the ring 7, a suitable operating handle 12 being rigidly connected with the shaft 10. The operating handle 12 is to be accessible to an operator on the ground. To maintain the ring 7 and wheel 1 against relative movement, during operation of the latter, any suitable means may be employed. However, there is here shown a spring pressed pawl 13 slidable in a housing 13^a on the handle 12, which pawl will normally engage a gear 14 or segment 14 on the shaft 2. The pawl may 105 be disengaged from the gear 14 by a grip

lever 15 on the handle 12 and connected to the pawl by a link 16. Suitable anti-frictional members, such as rollers 17 are provided between the ring 7 and wheel 1, each 5 roller being mounted between depending flanges 18 on the ring and spaced apart at suitable intervals around its circumference.

The embodiments in Figs. 1 and 2 particularly adapt the invention for use in 10 water currents, whereas the embodiment in Fig. 3 adapts the invention for wind currents, the construction being substantially the same as shown in Figs. 1 and 2 with the exception of the shafts 2 and 10 being inverted. Therefore, the same reference characters, distinguished by the exponents c , are used in both embodiments. It will be noticed also that in Fig. 3, the drive shaft 2 c 15 is hollow having the ring adjusting shaft 10 c extending therethrough. A gear 19 and 19 c is provided on each drive shaft 2 and 2 c to permit the power to be taken therefrom.

Having thus described the invention as at 20 present devised, it is to be understood that 25 certain changes in the construction and combination of parts may be made that fall within the scope of the appended claims.

What is claimed is:—

1. A current wheel having vanes normally 30 lying substantially at right angles to the wheel and collapsible under current pressure, a ring carried by the wheel and rotatable relatively thereto, and connections between said vanes and said ring.

35 2. A current wheel having vanes normally lying substantially at right angles thereto and collapsible under current pressure, a ring carried by the wheel and rotatable relatively thereto, and flexible connections between said vanes and said ring.

40 3. A current wheel having vanes normally lying substantially at right angles thereto and collapsible under current pressure, a

ring carried by the wheel and rotatable relatively thereto, flexible connections between 45 said vanes and said ring, a driven shaft having said wheel fast thereto, another shaft parallel with said first shaft and operatively connected with said ring, a handle means for operating said last shaft, and means normally maintaining said ring and wheel 50 against relative movement.

4. A current wheel having vanes normally lying substantially at right angles thereto and collapsible under current pressure, a 55 ring carried by the wheel and rotatable relatively thereto, said ring having a hub portion provided with internal gear teeth, a flexible connection between each vane and said ring, a pair of concentric shafts, one 60 having said wheel fast thereon and the other shaft having a gear thereon meshing with the teeth of said hub, means normally preventing relative movement between said ring and wheel, and an operating handle for said 65 other shaft.

5. A current wheel having vanes normally lying substantially at right angles thereto and collapsible under current pressure, a 70 ring carried by the wheel and rotatable relatively thereto, said ring having a hub portion provided with internal gear teeth, a flexible connection between each vane and said ring, a pair of nested shafts, one having said wheel fast thereon and the other shaft 75 having a gear thereon meshing with the teeth of said hub, an operating handle for said other shaft, a pawl on said handle engageable with the teeth on the wheel shaft, and a grip lever pivoted on the handle and 80 having connection with said pawl to disengage the same.

In testimony whereof we affix our signatures.

WINFIELD S. DRISCOLL.
WALTER F. DAVIS.
